CONCEALED KEY RECEPTACLE FOR DOORS

Thomas E. Cox, Birmingham, Ala.

Application September 13, 1937, Serial No. 163,644

6 Claims. (Cl. 70—447)

My invention relates to a new and improved receptacle for keys adapted to be mounted in the door or door frame in inconspicuous position when the door is open, and in concealed position when the door is closed.

The chief object of my invention is to devise a simple, inexpensive and readily formed or attached receptacle in which a door key, when not in use, can be kept always accessible and yet concealed.

One distinctive feature of my invention is that the receptacle is formed or placed at an upward incline so that the key will slip out by gravity when the slide door for the receptacle is opened.

A further distinctive feature of my invention lies in the fact that the slide door is so designed and mounted that in its closed position, with the key pressing against it, it will shift outward and stand flush with its facing plate, thus simulating a lock element for the door, but on pressing the slide in, it can be readily slipped up to release the key.

My invention in one form contemplates forming the key receptacle by boring or cutting out a suitable recess in the door stile.

My invention further contemplates the use of a casing to be set into the door jamb, either as a separate element or in association with the slide door plate so its presence will be less noticeable.

My invention further contemplates the novel details of construction and arrangements of parts, which are hereinafter more particularly described, reference being had to the accompanying drawings forming a part of this specification, in which:—

Fig. 1 shows my invention in front elevation mounted in the edge of the door stile.

Fig. 2 is a vertical cross section through the stile and key recess, showing the door plate in side elevation.

Figs. 3 and 4 are detail front and side views, the latter partly broken away, of the slide door plate.

Fig. 5 is a view corresponding to Fig. 1 of the key receptacle seated in the door jamb.

Fig. 6 is a vertical sectional view through the key receptacle and slide door plate.

Fig. 7 is an end view, and Fig. 8 a partial plan view of the slide door used in both forms of my invention.

Fig. 9 is a cross section of the slide door plate taken above the door and showing the latter

outwardly displaced to close flush the door opening in the plate.

Similar reference numerals refer to similar parts throughout the drawings.

In the embodiment of my invention illustrated in Figs. 1 to 4, I show the key receptacle formed in the door, preferably in its stile 10 immediately above the lock 11. I form in any convenient way in the edge of the stile a narrow hole or recess 12 which is pitched upwardly at an incline approximating 45°. This is preferably a narrow recess amply wide to receive an ordinary door key 13. To close the open end of this recess I provide a sliding door closure 20 comprising an outer, or face plate 14 adapted to be seated flush in the edge of the door stile and provided with a vertically elongated slot 15 in which the sliding closure 20 operates. The stock displaced to form this slot is left attached at the bottom end and is bent to extend up into the hole and forms a slide bottom 16 for the open end of the key recess 12. A guide plate 17 is mounted on the back of the face plate 14 and is formed with side flanges 18, which engage and space it from, the back of plate 14, and with end flanges 19 which close the ends of the slide way in which the vertically movable sliding closure works. I form a slot 23 in plate 17 corresponding to the opening 15 in the front plate and the slide strip 16 extends through this slot 23 into the recess 12 and prevents the key hanging between the plates 14 and 17. The door, as shown clearly in Figs. 7 and 8, has its central portion 20 raised and conforming in size to the opening 15 in the facing plate 14. This raised center 20 is offset from its side flanges 21 to an extent equal to the thickness of the face plate 14. Thus, in its lowered position the slide is adapted to shift outwardly so that its center 20 stands flush with, and closes the opening in the face plate 14. At its lower end the slide is formed with a very short lug or projection 22, just sufficient for the nail of a finger to catch under and lift the closure. By pressing inwardly against the closure it is displaced inwardly from its flush position into engagement with the guide plate 17 when it stands free to move upwardly in the slide way. When slid up to full open position the closure releases the key to slide out automatically into the hand of the operator. The door will close by gravity when released and when a key is in the pocket its endwise pressure against the closure will hold it in its flush position in plate 14, in which it closely resembles a latch element of the door lock. Screw holes 24 are formed

through the ends of both plates 14 and 17 and may be punched so as to interlock the plates together, or they may be spot welded or riveted.

In the embodiment of my invention illustrated in Figs. 5 and 6 I show a metallic key receptacle 25 associated with the closure elements 26 and 27, similar to 14 and 17, but here the plate is set into the door jamb 28 immediately above the keeper 29. The opening 15 is similar to that in the facing plate 14, and the open end of the receptacle is fitted against the guide plate 17 and may be secured thereto if desired in any suitable way. Due to the fact that the jamb is not thick enough to enable the key receptacle to be formed therein, it is necessary to utilize this metallic receptacle 25 formed of any suitable material and its lower bottom edge is formed into a down-turned flange 30 which hooks over the bottom of slot 23 in the plate 27. The seat cut in the jamb 28 snugly receives the back plate 27, the face plate 26, and the receptacle, and these parts may be left separate and made fast in any suitable way in the jamb, or all may be assembled before they are mounted. As shown the elements 25 are spot welded.

In operation, the key receptacle having been mounted, or formed as described, in the door jamb, a key can be very quickly and easily inserted into the receptacle or recess, and when the sliding door 20 is closed the presence of the receptacle will be unnoticeable. This provides a convenient way to keep an extra door key and it will be obvious that when the door is locked by the key in current use, the extra key is also locked up and is inaccessible.

When I refer to the receptacle as mounted in a door element I mean thereby to include either mounting or forming the receptacle in the door or in the door frame or jamb.

While I have shown my invention in but two forms, it will be obvious to those skilled in the art that it is not so limited, but is susceptible of various other changes and modifications, without departing from the spirit thereof, and I desire, therefore, that only such limitations shall be placed thereupon as are imposed by the prior

art or as are specifically set forth in the appended claims.

What I claim is:—

1. A receptacle for door keys comprising a means defining an upwardly inclined key-receiving recess in a door element, and a closure disposed and adapted to hold a key in said recess, the inclination of said recess being such that the key slides out by gravity. 5

2. A receptacle for door keys comprising a means defining an upwardly inclined key-receiving recess in a door element, and a closure for said recess comprising a sliding door and concealed guides therefor, the inclination of said recess being such that the key slides out by 15 gravity.

3. A receptacle for door keys comprising a means defining an upwardly inclined key-receiving recess in a door element, a sliding closure for said recess and comprising a face plate seated 20 flush in the door element and having an aperture, a closure guide on the back of said plate, the sliding closure being adapted in closed position to shift bodily outwardly into said aperture and assume a position flush with the outer face 25 of said face plate in response to the pressure of a key in said inclined recess.

4. A receptacle according to claim 1, in which the closure comprises an outer apertured plate having a portion thereof bent back into position 30 to form an inclined bottom slide for the key recess.

5. A key receptacle comprising in combination with a slide door plate having a door opening, a slide door, a back plate forming a vertical 35 slide guide for said door and having an opening opposite said door opening, and a key receptacle mounted behind said back plate in register with its opening and disposed at a sharp upward inclination. 40

6. A key receptacle according to claim 5, in which the receptacle has an open end engaging the back plate and provided with a bottom flange adapted to engage over the bottom edge of the opening in said back plate. 45

THOMAS E. COX.
